STARTER GEARING

Samuel Ysskin, Newark, N. J.

Application November 15, 1944, Serial No. 563,534

5 Claims. (Cl. 74—9)

1

This invention relates to improvements in starting devices, such as are used in the starting of internal combustion engines in automobiles. Such starting devices are customarily keyed to the armature of the starting motor and their construction is such that a pinion which is normally disengaged from the flywheel of the internal combustion engine will be engaged with said flywheel when the starting motor is energized.

Heretofore it has been found that such starting motors frequently become severely damaged and break in service.

It is the object of my invention to provide a starting device of the class described which is of such construction as to obviate the danger of injury to the parts thereof when subjected to normal operating conditions or when subjected to severe overloading.

A further object of my invention is to provide a starting device which is so designed as to be rugged and efficient in operation so as to assure the functioning thereof without danger of breaking down in service.

An embodiment of a structure employing my invention is shown in the accompanying drawings and described in detail in the ensuing specification. This embodiment is merely by way of example and my invention is not limited thereto but includes all other forms which would come within the scope of the appended claims. In the drawings:

Fig. 1 is a top plan view of a starting device embodying my invention, with the pinion thereof shown in its normal inoperative location,

Fig. 2 is a similar view partly broken, showing the relative juxtaposition of the parts on actuation thereof, with the pinion shifted into operative position,

Fig. 3 is an elevational, partly fragmentary view taken on line 3—3 of Fig. 1, in the direction of the arrows,

Fig. 4 is a vertical, longitudinal sectional view taken on line 4—4 of Fig. 3, in the direction of the arrows, and

Fig. 5 is a perspective view of a cam member employed in carrying out my invention.

Referring to the drawings, in Fig. 4, the starting device of my invention, is shown to comprise a tube 10 on which the pinion 11 is slidably arranged, said pinion being keyed to or formed integral with the collar member 12, the outer end of which is provided with recesses 13 for the reception of radial arms 31 of web 30 having recesses 32 (see Figs. 1 and 3) to slidably receive the spline lugs 14 depending from cam member 15. A cushion ring 16 is positioned in collar 12, being interposed therein between the end 19 of the cam 15 and the seat 17 of the collar 12. Washers 18, 18a are preferably interposed between the cushion member 16, and collar seat 17, and the

splined end 19 of cam 15 (see Figs. 2 and 3) the parts being normally maintained against displacement within the collar member 12 by snap ring 20 disposed within an internal recess adjacent the open end of the collar member 12, washer 18b being positioned in the collar member 12 adjacent snap ring 20, against the spider 30 and the forward edge of the spline lugs 14, to prevent the parts from moving out of the open face of the collar 12; at the same time, the spline lugs, on movement of the cam member 15 from which they depend toward the seat 17 of the collar, may freely move in the recesses 32 in spider 30 (see Figs. 2 and 3) to compress the cushion member 16 against said seat.

The tube 10 is preferably provided at the end nearest the pinion with a head or stop member 21 which may be formed integral therewith or may be a separate member secured thereto in any desired or convenient manner, said stop member 21 being provided with an internal circumferential recess 22 for reception of one end of a spring 23, the opposite end of said spring bearing against the pinion 11 to normally urge the latter away from said head 21 and out of the vertical plane of the engine flywheel. The driving cam member 24 is fixed to the tube 10 in any suitable manner, such as by bolt 29 passing through said cam member and tube and projecting through an aperture in the tube for reception in a recess in the armature shaft S. received in said tube 10. The tube 10 is preferably provided with a keyway 33 at the end remote from member 21 for reception of a key on the armature shaft (see Fig. 3). The cam members 15 and 24 are provided with cam surfaces 25 and 26, respectively, the ends of the respective cam surfaces being connected by flat shoulder portions 27 and 28 respectively, see Figs. 5 and 2.

In operation, the device is assembled as shown in Fig. 1, with the tube 10 keyed to the armature of the starting motor in any convenient or desired manner. The pinion 11, collar member 12 and splined cam member 15 are normally urged to the position shown in Figs. 1 and 4 wherein the pinion is not engaged with the motor flywheel, by the spring 23.

When the starting motor is energized, the rotation of the starting motor armature "whips" the tube 10 into rotation therewith. The sudden "whip" action causes the cam surfaces of the cam member 24 to engage the cam surfaces of the cam member 15, causing the latter to slide or shift on the sleeve 10 into recesses 32 of the spider 30 and, through the medium of cushion member 16 which is thereby compressed, shifting the collar member 12 (and thereby the pinion 11) into the operative position of the parts shown in Fig. 2.

The cushion member 16 is of such characteris-

tics that in the normal operation of the parts, in order to shift the pinion 11 for engagement with the flywheel, the cam member 15 (and its spline lugs 14 and washers) will in moving from the position shown in Fig. 1 to that shown in Fig. 2, compress member 16 partially (the cam surfaces 26 and 25 being only partially engaged in said operation, see Fig. 2).

When the parts are in the operative position shown in Fig. 2 the pinion 11 abuts the stop member 21 which precludes further lateral displacement of the pinion and collar.

In the event that the parts are subjected to the operation of unusual force the only effect would be to cause the cam surfaces 25, 26 to slide past the ledge portions 27, 28 thereof so that the parts would return to the position shown in Fig. 1; the member 16, when subjected to unusual pressure, compresses further than shown in Fig. 2 to permit the full rotative movement of the cam surfaces past the ledge portions thereof, as described.

It will be apparent, from an inspection of Fig. 4, that the cushion ring 16, which may be made of rubber or other yieldable material, and which is interposed between the splined end of the cam 15 and the seat 17 of the collar 12, assures the smooth and positive operation of the parts, urging the collar member 12 and its pinion 11 laterally against the tension of the spring 23, which is compressed into the recess 22 as shown in Fig. 2. The parts will be returned to their inoperative position shown in Fig. 1, responsive to the rotation of the flywheel, when the engine with which said flywheel is associated has started, in a manner apparent to those skilled in this art.

While I have shown and described the cushioning member 16 as being preferably a rubber ring, it will be apparent that other resilient means, equivalent thereto, may be substituted therefor within the scope of this invention; the terms "cushioning ring" or "cushioning member" wherever used in this specification and claims shall be deemed to include such equivalents.

While I have shown and described the cam members 24 and 15 provided with generally arcuate cam faces 25 and with shoulder portions 27 and 28 defining the ends of said cam faces, any other cam means may be substituted therefor in carrying out my invention within the scope of this invention.

Having thus described my invention what I claim as new and desire to secure by Letters Patent, is:

1. A mechanism for actuating a starter pinion fixed to a collar into mesh with an engine flywheel on actuation of the starter motor, said mechanism comprising a web member, complementary means on said web member and collar to position the web member in the collar, a cushion ring positioned in the collar, a cam member, complementary means on the cam member and web member to slidably spline said cam member in the web member, and a second cam member adapted on actuation of the starter motor to have camming engagement with the first mentioned cam member to slide the latter in the web against the cushion member, to compress the latter against the collar, shifting the collar to move the pinion fixed thereto into mesh with the engine flywheel.

2. A mechanism for actuating a starter pinion fixed to a collar into mesh with an engine flywheel on actuation of the starter motor, said mechanism comprising a web member, means to

position the web member in the collar, a cushion ring positioned in the collar, a member, spline lugs on said member, said web member being provided with means to slidably receive said splined member in the web member, and a second member adapted on actuation of the starter motor to engage the first mentioned member to slide the latter in the web against the cushion member, to compress the latter against the collar, shifting the collar to move the pinion fixed thereto into mesh with the engine flywheel.

3. A mechanism for actuating a starter pinion fixed to a collar into mesh with an engine flywheel on actuation of the starter motor, said mechanism comprising a web member provided with radial arms, said collar having recesses to receive said arms to position the web member in the collar, a cushion ring positioned in the collar, a cam member, spline lugs on said cam member, said web member having recesses to slidably receive the spline lugs of said cam member, and a second cam member adapted on actuation of the starter motor to have camming engagement with the first mentioned cam member to slide the latter in the web against the cushion member, to compress the latter against the collar, shifting the collar to move the pinion fixed thereto into mesh with the engine flywheel.

4. A mechanism for actuating a starter pinion fixed to a collar into mesh with an engine flywheel on actuation of the starter motor, said mechanism comprising a web member, means to position the web member in the collar between the web member and collar, said web member having splining means, and complementary separable means driven by the starter motor shaft, one of said complementary means engaging said web member splining means and adapted, on actuation of the starter motor, to be at least partially separated from the other complementary means and moved in said web member against the means in the collar, shifting the collar to move the pinion fixed thereto into mesh with the engine flywheel.

5. A mechanism for actuating a starter pinion fixed to a collar into mesh with an engine flywheel on actuation of the starter motor, said mechanism comprising a web member, means to position the web member in the collar, a compressible thrust ring positioned in the collar, said web member having splining means, and complementary separable means driven by the starter motor armature shaft, one of said complementary means engaging said web member splining means and adapted, on actuation of the starter motor, to be at least partially separated from the other complementary means and moved in said web member against the thrust ring to compress the latter against the collar, shifting the collar to move the pinion fixed thereto into mesh with the engine flywheel.
